UNITED STATES PATENT OFFICE

172,360

CANDLESTICK

James Russell Price, Centerdale, R. I., assignor to Gorham Manufacturing Company, Providence,
R. I., a corporation of Rhode Island

Application April 13, 1953, Serial No. 24,471

Term of patent 7 years

(Cl. D48—2)

To all whom it may concern:

Be it known that I, James Russell Price, a citizen of the United States of America, residing at Centerdale, Rhode Island, have invented a new, original, and ornamental Design for Candlestick, of which the following is a specification, reference being had to the accompanying drawings, forming part thereof.

Fig. 1 is a side elevational view of a candlestick showing my new design;

Fig. 2 is a top plan view;

Fig. 3 is a bottom plan view; and

Fig. 4 is a vertical section through Fig. 1.

I claim:

The ornamental design for a candlestick, as shown.
